UNITED STATES PATENT OFFICE.

HENRY I. WRIGLEY, OF CHICAGO, ILLINOIS, ASSIGNOR TO UNIVERSAL DRAFT GEAR ATTACHMENT COMPANY, OF CHICAGO, ILLINOIS, A CORPORATION OF ILLINOIS.

DRAFT-PLATE FOR RAILWAY-CARS.

1,156,573.

Specification of Letters Patent.

Patented Oct. 12, 1915.

Application filed September 23, 1914. Serial No. 863,111.

To all whom it may concern:

Be it known that I, HENRY I. WRIGLEY, a citizen of the United States, and resident of Chicago, county of Cook, and State of Illinois, have invented certain new and useful Improvements in Draft-Plates for Railway-Cars, of which the following is a specification, and which are illustrated in the accompanying drawings, forming a part 10 thereof.

The invention relates to plates adapted to be attached to the sills of a railway car and to serve as means for transmitting thereto draft and buffing stresses from the 15 coupler.

More specifically it relates to plates of this character which constitute in themselves buffing blocks for receiving at their forward ends excessive buffing blows from the coupler horn, and which are also provided with draft shoulders or horns for engaging the inner face of the end sill of the car.

In draft plates of this type it is important that the forward end constituting the 25 buffing block should bear firmly against the outer face of the end sill and that the draft horn should bear firmly against the inner face of this sill. Car sills vary in size and are not fitted with exactness and 30 it therefore frequently happens that the draft and buffing horns of the plate will not fit snugly against the timber. Looseness of fit may also be developed with service, partly due to the shrinkage of the material 35 and partly due to its compression or abrasion.

The object of the present invention is to provide a wedging element fitting between the draft horn and end sill, and so constructed 40 that it will automatically adjust itself and secure a tight fit, and will maintain such fit automatically as it will advance to take up any looseness which may develop in the course of service.

An embodiment of the invention is hereinafter described, and is illustrated in the accompanying drawings, in which—

Figure 1 is a detail longitudinal section 50 of a car showing the draft plate partly in elevation and partly in section; Fig. 2 is a detail plan section of the same; Fig. 3 is a detail section similar to Fig. 1, showing a slightly modified form of car construction; and Fig. 4 is a detail in perspective, 55 and partly in section, of the draft plate.

The end sill of a car is represented at 10, and one of its center sills at 11. The draft plate, generally represented by the numeral 12, may be of any preferred form of construction as to the arrangement and 60 location of its draft and buffing shoulders and as to the means for attaching it to the center sill of the car. It projects forwardly, as shown at 13, under and beyond the end sill 10, and is provided with an upstanding 65 buffing horn 14 for receiving on its forward face 15 the blows from the buffing horn 16 of the coupler 17, and for bearing with its inner face against the front face of the end sill.

Back of the end sill there is provided an upstanding horn, generally represented by the numeral 18, this horn being located adjacent the inner face of the center sill 11. The forward face of the horn 18 is inclined 70 downwardly and forwardly, as shown at 19, and there is interposed between this face and the sill 10 a wedge-block 20, having a rearward inclined face conforming to the inclined face of the horn and a forward vertical face for engaging the sill, this forward face being preferably roughened for increasing its frictional engagement. The wedge-block will automatically drop into place between the horn and sill, and will tend to 75 work down under the influence of the vibration or weaving of the car frame and thus firmly clamp the sill between the two draft arm horns.

The important part of the invention consists in the means for connecting the wedge-block with the draft horn. To this end the horn is provided with lateral flanges 21, 22, projecting in opposite directions from its web 23. The wedge-block 20 is provided 80 with a pair of rearwardly extending lugs 24, 25, which embrace the front end of the horn, extending backwardly beyond its flanges 21, 22, and each being provided with an 85 in-standing boss 26 which hooks around or under the horn flange with which it co-operates. To facilitate assembling, one of the flanges, as 21, is recessed at its rearward end, as shown at 27, to permit the boss 26 to enter, and the other flange, 22, recedes at its rearward end, as shown at 28, for the same purpose. The block 20 is first placed over the horn in the dotted lines position of Fig. 1, and then pushed forwardly and downwardly into place. By a blow of a hammer 100 105 110

upon the rearward end of the flange 22, at the point at which it angles inwardly, it is bent down, as indicated at 29 (Fig. 1), thereby preventing accidental or intentional removal of the block.

The buffing horn 14 extends laterally to the center line of draft, and is provided with an upstanding flange 30 adapted to bear against and be riveted to the corresponding flange of the companion arm, thereby providing greater rigidity of the buffing element.

It is the practice with some car builders to extend the end sheathing 31 of the car downwardly over the front face of the end sill, as shown in Fig. 3. When this construction is followed, the sheathing interposed between the buffing horn and the sill proper becomes in effect a part of the sill and for the purposes of this invention is treated as such.

I claim as my invention,—

1. A draft plate having a draft horn offset inwardly from the body of the plate, the

front face of the horn being inclined and provided with lateral flanges, a wedge-block applied to such inclined face and having lugs hooking around the flanges.

2. A draft plate having a draft horn, the front face of which is inclined and provided with lateral flanges, a wedging block applied to such inclined face and having lugs hooking around the flanges, one of such flanges being recessed to permit the entrance of one of the lugs.

3. A draft plate having a draft horn the front face of which is inclined and provided with lateral flanges, a wedging block applied to such inclined face and having lugs hooking around the flanges, one of such flanges having a shouldered end adapted to be bent down to prevent the disengagement of the lug.

HENRY I. WRIGLEY.
